UNITED STATES PATENT OFFICE.

THEODORE VARNEY, OF SEWICKLEY, PENNSYLVANIA, ASSIGNOR TO ALUMINUM COMPANY OF AMERICA, OF PITTSBURGH, PENNSYLVANIA, A CORPORATION OF PENNSYLVANIA.

CLAMP DEVICE FOR ELECTRIC CONDUCTORS.

1,420,790.

Specification of Letters Patent. Patented June 27, 1922.

Application filed August 14, 1920. Serial No. 403,456.

To all whom it may concern:

Be it known that I, THEODORE VARNEY, a citizen of the United States, and a resident of Sewickley, in the county of Allegheny and State of Pennsylvania, have invented certain new and useful Improvements in Clamp Devices for Electric Conductors, of which the following is a specification.

This invention relates to a clamp intended 10 to hold two wires or cables together in parallel position, usually for the purpose of providing electrical connections between two cables, but sometimes for mechanical reasons.

15 It has for its object to provide a clamp for this purpose which shall be adjustable for use with various sizes of cable, and will effectively engage both cables even though they be of different diameters.

20 The invention may be clearly understood by reference to the accompanying drawings, in which,

Fig. 1 is a side elevation of the clamp;

25 Fig. 2 is an end elevation thereof, showing parallel cables of the same size and having a relatively small diameter being engaged by the clamp;

Fig. 3 is a plan of the clamp;

30 Fig. 4 is an end elevation similar to Fig. 2 in which parallel cables of the same size but having relatively large diameters are being engaged;

35 Fig. 5 is a similar end elevation showing parallel cables of different diameters being engaged;

Fig. 6 is an end elevation of one of the clamping plates; and

Fig. 7 is a top view thereof.

In the drawings, the clamp A comprises 40 two plates or members 5 and 6 having central openings 7 therein through which passes a bolt 8 provided on one end with a head 9 and on its opposite threaded end with a lock washer 10 and a nut 11. On 45 the outer faces of the members 5 and 6 and surrounding the openings 7 are rounded projections or surfaces 7'. By reason of these rounded projections, the members may be tightly forced together, even though they 50 are at an angle to each other, as shown in Fig. 5.

On the inner faces of said members and along each side thereof are grooves or curved seat portions 12 for the cables or wires, the

cables being indicated by the letter B. Extending outwardly from the grooved seats are spaced apart curved extensions 13. The extensions 13 on one side of one member are preferably staggered with relation to those on the other side. Extending inwardly 60 from the curved seat portions 12 are spaced apart lugs or projections 14 which are of less height than the curved extensions 13. The lugs 14 are staggered with relation to the extensions 13. The extensions 13 and 65 the lugs 14 on one side of one plate 5 are also staggered with relation to those on the adjacent side of the other plate 6. Thus, the projections 14 and the extensions 13 on the inner faces of the plates mesh or interlock so that they may be held close together, as shown in Fig. 2, to permit small cables 70 to be clamped. This interlocking also prevents any endwise or sidewise movement of the plates relatively to each other.

75 When sufficiently large cables are being connected, the projections 14 will be raised out of interlocking relation but the rounded extensions 13 will still interlock, as shown in Fig. 4. By reference to Fig. 5, it will be 80 seen that one cable or wire of large diameter and one of small diameter may be connected in the same clamp.

It will be observed that the curved extensions 13 and the rounded sides of the 85 raised portions or projections 14 serve to retain the cables in the grooved or curved seats 12. By properly positioning portions of parallel cables in the grooves on the opposite sides of the two plates and tightening 90 the nut 11 on the bolt 8, the two plates may be drawn tightly together to connect the cables.

What I claim is:

1. A clamp for parallel wires or cables 95 capable of use with wires or cables of varying diameters and for simultaneously clamping wires or cables of different diameters including a pair of opposed members each having interlocking portions, a plurality of 100 inwardly extending projections adapted to interlock, wire engaging seats disposed between the interlocking portions and the said projections, and means for securing the opposed members together.

105 2. A clamp for parallel wires or cables capable of use with wires or cables of varying and different diameters including a pair

- of opposed centrally apertured members each having a rounded projection on its outer face, interlocking portions, wire engaging seats, and a central bolt having means bearing upon the rounded projections of the opposed members.
3. A clamp for parallel wires capable of use with wires of varying and different diameters including a pair of opposed clamping plates each having interlocking curved extensions along their side edges, a series of projections along each side of the plates but spaced inwardly from the curved extensions on the adjacent surfaces of the plates adapted to interlock, wire receiving and clamping means formed between the extensions and projections, and means for clamping the plates together.
4. A clamp for parallel wires capable of use with wires of varying and different diameters comprising a pair of similar opposed clamping plates each having interlocking curved extensions along their side edges, a series of projections parallel with each side of the plates but spaced inwardly from the extensions on the adjacent surfaces of the plates and adapted to interlock, wire receiving and clamping means formed between the extensions and projections, and means including a central bolt for clamping the plates together.
5. A clamp for parallel wires comprising a pair of opposed clamping plates having parallel means thereon adapted to coact to engage the wire, spaced apart extensions on the outside edges of said means and on each plate which are adapted to interlock with similar extensions on the opposite plate, spaced apart projections adjacent the inside edges of said wire engaging means, said projections on the adjacent faces being adapted to interlock, and means for holding the plates in clamping position.
6. A clamp for parallel wires comprising a pair of opposed plates having parallel wire receiving grooves on their adjacent faces, curved spaced apart extensions along the sides of each plate and adjacent the grooves and so arranged that the extensions on one plate interlock with those on the other, lugs on the inner faces of said plates and adjacent the grooves, said lugs on opposite plates being adapted to interlock, and means for holding the plates in clamping relation.
7. A clamp for parallel wires comprising a pair of opposed plates having parallel wire receiving grooves on their adjacent faces, curved spaced apart extensions along the sides of each plate and adjacent the grooves and so arranged that the extensions on one plate interlock with those on the other, lugs on the inner faces of said plates and adjacent the grooves, said lugs on opposite plates being of less height than the curved extensions and adapted to interlock, and means for holding the plates in clamping relation.
8. A clamp for parallel wires comprising a pair of opposed plates, curved seat portions extending longitudinally along each side of said plates on the adjacent faces thereof, spaced apart interlocking extensions on the outsides of said seat portions, projections adapted to interlock adjacent inner sides of said seat portions, and means for holding the plates in clamped relation.
9. A clamp for parallel wires comprising a pair of opposed plates, curved seat portions extending along each side of said plates on the adjacent faces thereof, spaced apart extensions along the outside of said seat portions, the extensions on one side being staggered with relation to those on the other and with relation to those on the adjacent side of the opposite plate, spaced apart projections adjacent the inner sides of the seat portions and which are staggered with relation to said extensions, said extensions and projections being adapted to form wire engaging means, and means for holding the plates in clamped relation.
10. A clamp for wires or cables including a pair of opposed members, one of which has a rounded projection on its outer face, each member having interlocking portions and wire engaging seats, and means bearing upon the rounded portion for securing the opposed members together, said rounded portion co-acting with the securing means in such manner as to allow for the angular adjustment of said clamp members when being clamped together.

In testimony whereof I affix my signature in presence of two witnesses.

THEODORE VARNEY.
